UNITED STATES PATENT OFFICE.

WALTER W. KANTACK, OF ST. ALBANS, NEW YORK, ASSIGNOR TO ALFRED VESTER SONS, INC., OF PROVIDENCE, RHODE ISLAND, A CORPORATION OF RHODE ISLAND.

DESIGN FOR A BANDING FOR LIGHTING FIXTURES.

Application filed November 3, 1926. Serial No. 19,589. Term of patent 7 years.

To all whom it may concern:

Be it known that I, WALTER W. KANTACK, a citizen of the United States, residing at St. Albans, L. I., in the county of Queens and State of New York, have invented a new, original, and ornamental Design for a Banding for Lighting Fixtures, of which the following is a specification, reference being had to the accompanying drawing, forming part thereof, in which—

Fig. 1 is a front view of a section of banding showing my new design;
Fig. 2 is an edge view.

I claim:
The ornamental design for a banding for lighting fixtures, as shown.

WALTER W. KANTACK.
